UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed October 15, 1925. Serial No. 62,552.

This invention relates to stencil card holding and typing devices for typewriting machines, in which a card-holding frame is arranged to reciprocate tangentially to a 5 revoluble platen.

Some addressing machines are designed to use a card including a comparatively heavy paper or cardboard frame, having an opening across which is stretched a stencil sheet. 10 Besides typing the addresses upon the stencil sheet with the bare type, it is sometimes desirable to type some information upon both sides of the paper frame with the aid of the ribbon.

15 In my pending application, No. 43,492, filed July 14, 1925, a device is shown in which, while adapted for automatically controlling the ribbon so that it will be vibrated when the frame of the card is in the printing 20 field and silenced when the stencil-sheet is in the printing field, to facilitate typing upon the stencil-card, no provision was made for handling cards upon which it was desired to type on both sides thereof.

25 This invention is in the nature of an improvement on said application and contemplates to enlarge the scope of said device and to generally expedite the handling of the work.

30 According to certain features of this invention, the stencil-sheet is inserted in a card-holder tangentially disposed in front of the platen, and by rotating the platen the holder is lowered to a position for receiving the first line of typing upon the paper frame, at the upper edge thereof. While the card is in this position, the ribbon is vibrated at each key depression and when the card is elevated to present the stencil- 35 sheet to the printing field, the ribbon is silenced. Upon finishing typing on one side of the card, the same is withdrawn from the holder and is reversed and turned upside down, and is again inserted in the holder 40 to receive typing upon the back of the paper frame.

45 Since the device disclosed in said application includes means for controlling the ribbon-vibrating mechanism, and since said 50 means are controlled by the position of the card, it will be apparent that if the machine is set or timed to silence the ribbon when the lower portion of the card is in the printing field and to vibrate the ribbon when the

card is lowered, then upon reversing and 55 turning the card upside down the machine will be out of time, that is to say, it will vibrate the ribbon in front of the stencil window, and will silence the ribbon when the frame of the card is in the printing 60 field. This, of course, would render the device inoperative. However, in this invention, novel means are contrived whereby the card may be arrested while being inserted in the card-holder so that the lower portion of 65 the card will be presented to the printing field substantially in the upper portion of the holder, and thus, by a very simple and inexpensive device, one of the objects of the invention is accomplished.

70 One of the features of the invention relates, therefore, to means for controlling the position of the card in the card-holder. To this end, there are provided a pair of stop devices in the card-holder resiliently held in 75 the path of the card so that the bottom edge thereof may be supported by said stop devices. There are also provided a pair of manually operable handles connected to said stop devices, whereby the stop devices may 80 be rendered inoperative. The card will, of course, be then lowered all the way down so that its lower edge will strike the bottom of the card-holder. This, however, is only 85 done when it is desired to type upon the front side of the card.

Another feature of this invention relates to novel means for facilitating the replacement of a celluloid covering encircling a portion of the platen, said covering serving 90 as a backing for the types when cutting the stencil-sheet. According to this feature, there is provided a clamping member extending the full width of the platen which co-operates with a slot in the platen to hold 95 one edge of the celluloid. The other edge of the celluloid may be bent inwardly to engage with a second slot in the platen, so that it may be stretched between the two slots. The clamping member is held in effective position by means of a spring and is provided with a finger-piece for rendering the clamp ineffective.

100 Other features and advantages will hereinafter appear.

105 In the accompanying drawing, Figure 1 is a front view, in elevation, of an Underwood typewriting machine having

the invention applied thereto and shows the card in its lowermost position.

Figure 2 is a similar view, showing the card inserted half way in the card-holder, the 5 lower edge of the card being arrested by stop devices in the card-holder.

Figure 3 is a cross-sectional view, in elevation, through the center of an Underwood typewriting machine and shows novel means 10 for holding a celluloid backing around the platen of the machine.

Figure 4 is a cross-sectional view of the platen and shows the means for holding the celluloid in its released position.

15 Figure 5 is a plan view of the platen.

Figure 6 is a cross-sectional view through line 6—6 of Figure 2.

This invention is illustrated as applied to an Underwood standard typewriting machine, and the invention is especially adapted 20 for handling stencil-cards used in some types of addressing machines. The stencil-cards usually comprise a heavy paper frame 10 in which there is provided an opening 11 across 25 which there is stretched a stencil-sheet 12.

The card is inserted in a card-holder 13 arranged to reciprocate tangentially to a platen 14 revolvably mounted upon a platen-frame. The card is then lowered by rotating the 30 platen in a counter-line-feeding direction by means of a handle 15, so that the first line of typing may be printed upon the paper frame, at the upper edge thereof. The card is then line-spaced by means of a line-space 35 handle 16, and other lines are typed upon the frame of the card.

In my said pending application, there is provided mechanism whereby the ribbon 40 may be vibrated in certain typing zones of the card and silenced when the stencil-sheet is presented to the printing field. Said mechanism is operated by a universal bar 17 which is vibrated by type-bars 18 at each key-depression. There is also provided mechanism 45 for controlling the ribbon-vibrator relatively to the position of the card-holding frame in front of the platen, which may include an actuating member 19 secured to the card-holding frame at the lower edge thereof, 50 which member engages with teeth 20 of a plate 21 rockably mounted upon a pivot 22 and actuates, by means of a link 23 operatively connected thereto, the means whereby the ribbon is either connected to the universal bar or disconnected therefrom.

Since the ribbon is automatically vibrated 60 when the card is lowered to present the frame thereof to the printing field, and is silenced when the stencil-sheet is presented to the printing field, it follows that if the card is turned upside down in order to type upon the back of the card frame, then the card will be out of time with the ribbon-vibrating mechanism, that is to say, the ribbon would 65 be silenced when typing upon the frame, and

would conversely be rendered operative when typing upon the stencil-sheet.

In order to eliminate this condition which would render the machine inoperative when typing upon the back of the card, there is provided novel mechanism for the purpose of synchronizing the operation of the ribbon with the position of the card, so that the card will be positioned in the card-holder to suit the controlling mechanism of the ribbon. To this end, there is provided a pair of stop devices 24 pivotally mounted on studs 25 secured to the card-holder, the stop devices being controlled by handles 26 also pivotally mounted upon the holder and operatively connected to the stop devices by means of a pin-and-slot arrangement 27. The card-holder comprises a back-plate 28 having racks 29 secured thereto, and is provided with an undercut 30 forming a recess in 35 which the card is lodged. In order to hold the card in the recess, there is provided a pair of plates 31 secured to the holder in a manner to provide guides for the edges of the card. Said plates may also serve as 40 means for preventing accidental displacement of the card and for positioning the stop devices 24 either in effective or ineffective position. The plates are provided with finger-pieces 32, forming an integral part 45 thereof, and with spring clips 33, which may also form an integral part of said plates. It will be noted, by referring to Figures 2 and 6, that the stop devices are mounted in a recess 34 in the holder and are covered by 50 the plates 31. In order to position the stop devices, the clips 33 are provided with detents 35 engaging with either of two holes 36 in said stop devices. The handles 26 are pivotally mounted upon shoulder screws 37, 55 which serve also as means for securing the plates 31 to the holder 13, and are provided with slots 38 for engagement with studs 39 fast to the stop devices 24, the studs 39 protruding through slots 40 in the plates 31, 60 which may be further secured to the holder by means of screws 41.

When typing upon the stencil-sheet with the bare type, it is customary to provide a backing encircling the platen so as to protect both the platen and the types, and at the same time facilitate the cutting of the stencil. Novel means are provided in this invention to facilitate the removal of the backing when worn out, so that a fresh one may 65 be substituted therefor.

The backing may be in the form of a celluloid strip 42 extending substantially the full width of the platen and secured to the platen by means of a clamping member 45 which also extends the full width of the platen. The edges of the celluloid are bent inwardly and engage with slots 43 and 44 in the platen, the latter being made large enough to house the clamping member 45,

as shown in Figures 3 and 4, in which the clamping member is shown respectively in its closed and open positions. The platen is supported upon a platen-shaft 46 journaled in end plates 57 of the platen-frame, and is provided with a finger-piece 47 at the end thereof, the platen being secured to the shaft by means of end flanges 48 which carry fast thereto pinions 49 designed to engage the racks 29 on the card-holder. The clamping member 45 may be constructed in the form of a bail-piece having side ears 50 and holes 51 therein co-operating with turned-down ends of studs 52 screwed into the flanges 48. The clamping member is pivotally mounted on said studs 52 and is held in its effective position by means of a spring 53 sunk into a hole 54 in the body of the platen, the spring being held in alignment with the hole by means of a stud 55 fast to the clamping member. In order to release the grip of said clamping member, there is provided a finger-piece 56 forming an integral part thereof, the finger-piece being operated in a manner as shown in Figure 4.

Variations may be resorted to within the scope of the invention, and portions of the improvements may be used without others.

Having thus described my invention, I claim:

1. The combination with a typewriting machine having a card-holding frame arranged to reciprocate tangentially in front of a revolubly mounted platen, and means for vibrating a ribbon in front of the types when the card-holding frame is in its lower position and for silencing the ribbon when the frame is in upper position, of means on the sides of said frame effective for engaging the bottom edge of a card in said frame for locating the card to receive ribbon typing upon the lower edge portion of the card.
2. The combination with a typewriting machine having a card-holding frame arranged to reciprocate tangentially in front of a revolubly mounted platen, and means for vibrating a ribbon in front of the types when the card-holding frame is in its lower position and for silencing the ribbon when the frame is in upper position, of means for controlling the position of the card in the frame, so that the card may be located to receive typing with the aid of the ribbon upon the lower portion of the card, said last-mentioned means including a pair of stop-devices controlled by handles conveniently placed above the card-holding frame.
3. The combination with a typewriting machine having a card-holding frame arranged to reciprocate tangentially in front of a revolubly mounted platen, and means for vibrating a ribbon in front of the types when the card-holding frame is in its lower position and for silencing the ribbon when the frame is in upper position, of means for controlling the position of the card in the frame, so that the card may be located to receive typing with the aid of the ribbon upon the lower portion of the card, said last-mentioned means including stop-devices 70 pivotally mounted upon the card-holding frame whereby the card may be arrested by its bottom edge, and means for positioning the stop-devices in either effective or ineffective position said last-mentioned means including a spring having a detent at the end, said detent co-operating with holes in the stop-devices.
4. The combination with a typewriting machine having a card-holding frame arranged to reciprocate tangentially in front of a revolubly mounted platen, and means for vibrating a ribbon in front of the types when the card-holding frame is in its lower position and for silencing the ribbon when the frame is in upper position, of means for controlling the position of the card in the frame, so that the card may be located to receive typing with the aid of the ribbon upon the lower portion of the card, said last-mentioned means including stop-devices pivotally mounted upon the card-holding frame whereby the card may be arrested by its bottom edge, means for positioning the stop-devices in either effective or ineffective position, and means for controlling the position of the stop-devices, said last-mentioned means including handles pivotally mounted upon the frame, and means for operatively connecting the ends of said handles with the stop-devices.
5. The combination with a typewriting machine having a card-holding frame arranged to reciprocate tangentially in front of a revolubly mounted platen, and means for vibrating a ribbon in front of the types when the card-holding frame is in its lower position and for silencing the ribbon when the frame is in upper position, of means for controlling the position of the card in the frame, so that the card may be located to receive typing with the aid of the ribbon upon the lower portion of the card, said last-mentioned means including stop-devices pivotally mounted upon the card-holding frame whereby the card may be arrested by its bottom edge, means for positioning the stop-devices in either effective or ineffective position, and means for controlling the position of the stop-devices, said last-mentioned means including handles pivotally mounted upon the frame, and means for operatively connecting the ends of said handles with the stop-devices, said last-mentioned means including studs fast to the stop-devices, said studs co-operating with slots in the handles.
6. The combination with a typewriting machine having a revoluble platen and a card-holding frame arranged to reciprocate in front thereof, said frame including a rear

plate having a cut-away portion at the center of substantially the same width as the platen, a recess cut into said frame for receiving the side edges of a card, a recess at the bottom of the frame for receiving the bottom edge of the card, a pair of plates secured to the sides of said frame to hold the edges of the card in said recess, and means for frictionally holding the card in the card-holding frame, said means including a pressure finger on each of said plates, each finger forming an integral part of said plates, and being bent inwardly to bear upon the edges of the card, and bent forwardly at the top thereof to form a throat for readily inserting the card.

7. The combination with a typewriting machine having a revoluble platen and a card-holding frame arranged to reciprocate in front thereof, said frame including a rear plate having a cut-away portion at the center of substantially the same width as the platen, a recess cut into said frame for receiving the side edges of a card, a recess at the bottom of the frame for receiving the bottom edge of the card, means for locating the card in the card-holding frame, so that the bottom edge of the card will be arrested a considerable distance from the recess at the bottom of the card-holding frame, said means including stop-devices, pivotally mounted on said frame at the sides thereof, and means for controlling the position of said stop-devices to render them either effective or ineffective.

8. The combination with a typewriting machine having a revoluble platen and a card-holding frame arranged to reciprocate in front thereof, said frame including a rear plate having a cut-away portion at the center of substantially the same width as the platen, a recess cut into said frame for receiving the side edges of a card, a recess at the bottom of the frame for receiving the bottom edge of the card, means for locating the card in the card-holding frame, so that the bottom edge of the card will be arrested a considerable distance from the recess at the bottom of the card-holding frame, said means including stop-devices, pivotally mounted on said frame at the sides thereof, and means for controlling the position of said stop-devices to render them either effective or ineffective, said last-mentioned means including a pair of handles pivotally mounted on said frame and means for operatively connecting said handles to said stop-devices.

9. The combination with a typewriting machine having a revoluble platen and a card-holding frame arranged to reciprocate in front thereof, said frame including a rear plate having a cut-away portion at the center of substantially the same width as the platen, a recess cut into said frame for re-

ceiving the side edges of a card, a recess at the bottom of the frame for receiving the bottom edge of the card, a pair of plates secured to the sides of said frame to hold the edges of the card in said recess, means for locating the card in the card-holding frame to arrest it a considerable distance from the bottom recess in said frame, said means including stop-devices pivotally mounted on the sides of said frame, a recess in said frame for housing said stop-devices, and means for controlling the position of said stop-devices, said last-mentioned means including finger-pieces pivotally mounted on said pair of plates and means for operatively connecting said finger-pieces to said stop-devices.

10. The combination with a typewriting machine having a revoluble platen and a card-holding frame arranged to reciprocate in front thereof, said frame including a rear plate having a cut-away portion at the center of substantially the same width as the platen, a recess cut into said frame for receiving the side edges of a card, a recess at the bottom of the frame for receiving the bottom edge of the card, a pair of plates secured to the sides of said frame to hold the edges of the card in said recess, means for locating the card in the card-holding frame to arrest it a considerable distance from the bottom recess in said frame, said means including stop-devices pivotally mounted on the sides of said frame, a recess in said frame for housing said stop-devices, and means for controlling the position of said stop-devices, said last-mentioned means including finger-pieces pivotally mounted on said pair of plates and means for operatively connecting said finger-pieces to said stop-devices, 100

11. The combination with a typewriting machine having a revoluble platen and a card-holding frame arranged to reciprocate in front thereof, said frame including a rear plate having a cut-away portion at the center of substantially the same width as the platen, a recess cut into said frame for receiving the side edges of a card, a recess at the bottom of the frame for receiving the bottom edge of the card, a pair of plates secured to the sides of said frame to hold the edges of the card in said recess, means for locating the card in the card-holding frame to arrest it a considerable distance from the bottom recess in said frame, said means including stop-devices pivotally mounted on the sides of said frame, a recess in said frame for housing said stop-devices, means for controlling the position of said stop-devices, said last-mentioned means including finger-pieces pivotally mounted on said pair of plates and 120

means for operatively connecting said finger-pieces to said stop-devices, and means for frictionally holding the stop-devices in either effective or ineffective position, said last-mentioned means including spring-strips forming an integral part of said pair of plates, said strips having detents at the ends and the detents co-operating with holes in the stop-devices.

10 12. A platen for a stencil-card-typewriting machine, having a celluloid strip, covering a portion of the periphery of said platen, and means for holding said strip against displacement, said means including a slot in 15 said platen extending substantially the full width thereof, said slot being designed to receive a bent edge of said strip, a second slot for receiving the other edge of the strip and means for locking one of the edges in 20 one of the slots, the other edge being bent inwardly in a manner to prevent its being disengaged without first releasing the locking means.

13. A platen for a stencil-card-typewriting machine, having a celluloid strip, covering a portion of the periphery of said platen, and means for holding said strip against displacement, said means including a slot in 25 said platen extending substantially the full width thereof, said slot being designed to receive a bent edge of said strip, a second slot for receiving the other edge of the strip and means for locking one of the edges in 30 one of the slots, the other edge being bent inwardly in a manner to prevent its being disengaged without first releasing the locking means, said last-mentioned means including a bail-piece pivotally mounted in end plates 35 of the platen, said bail-piece having a clamping edge effective to grip the strip against one side of the slot, means for resiliently holding the bail-piece in its effective position, and means for releasing the grip of the clamping piece.

40 14. A platen for a stencil-card-typewriting machine, having a celluloid strip, covering a portion of the periphery of said platen, and means for holding said strip against displacement, said means including a slot in 45 said platen extending substantially the full width thereof, said slot being designed to receive a bent edge of said strip, a second

slot for receiving the other edge of the strip and means for locking one of the edges in 55 one of the slots, the other edge being bent inwardly in a manner to prevent its being disengaged without first releasing the locking means, said last-mentioned means including a bail-piece pivotally mounted in 60 end plates of the platen, said bail-piece having a clamping edge effective to grip the strip against one side of the slot, means for resiliently holding the bail-piece in its effective position, and means for releasing the grip of the clamping piece, said last two 65 mentioned means including a spring sunk into a hole in the platen, said spring being effective to rock the bail-piece, and a finger-piece, adjacent the spring, effective to compress the spring and to rock the bail-piece 70 out of engagement with the strip.

15. A platen for a stencil-card-typewriting machine, having a celluloid strip, covering a portion of the periphery of said platen, and means for holding said strip against 75 displacement, said means including a pair of slots in the platen extending substantially the full length thereof, said slots being oblique to the periphery of the platen and being designed to receive inwardly-bent edges 80 of said celluloid strip, and clamping means in one of the slots to resiliently hold one edge of the celluloid strip against one side of the slot.

16. A platen for a stencil-card-typewriting machine, having a celluloid strip, covering a portion of the periphery of said platen, and means for holding said strip against displacement, said means including a pair of 85 slots in the platen extending substantially the full length thereof, said slots being oblique to the periphery of the platen and being designed to receive inwardly-bent edges 90 of said celluloid strip, and clamping means in one of the slots to resiliently hold one edge of the celluloid strip against one side of the slot, said last-mentioned means including a bail-piece pivotally mounted at the 95 ends of the platen, said bail-piece having a clamping edge, a spring to rock the bail-piece so as to grip the strip, and means for manually releasing the grip of said bail-piece.

ALFRED G. F. KUROWSKI.
